PACKAGING CONTAINER

Robert L. Cave, Manhattan, Kans., assignor to Buckeye
Bait Corporation, Council Grove, Kans., a corporation of Ohio

Filed July 29, 1963, Ser. No. 76,001

Term of patent 14 years

(Cl. D58—12)

Fig. 1

The left side elevation of the design is the same as the right side elevation.

The essential features of my design include a three sided packaging container having two sides of substantially equal length and the third side of an arcuate configuration with each of said sides having a series of ribs extending vertically along a portion thereof, all as shown.

I claim:

The ornamental design for a packaging container, substantially as shown and described.
